UNITED STATES PATENT OFFICE

JOHN GREEN, OF OAKLAND, CALIFORNIA

FRAME CONSTRUCTION

Application filed May 14, 1929. Serial No. 362,896.

My invention relates to improvements in frame constructions, particularly useful in the erection of the structures commonly known as steel buildings, although also useful for other purposes, including the building or erection of the metal frames of toy structures and the like.

One of the objects of the present invention is the provision of certain means whereby improved connections may be made between the girders and columns and other members forming portions of the frame or skeleton of the building or structure, whereby most of the riveting, or welding, as the case may be, at the building site during the erection of the frame, will be obviated, thereby not only greatly expediting the work of construction and thereby effecting a substantial saving in labor cost, but also eliminating the noises made by the workmen in securing the rivets (which noises have lately been found decidedly objectionable particularly in the larger cities throughout the country), as well as materially shortening the time during which portions of the adjacent side-walls and streets must be set aside for the use of the contractor erecting the building.

With the foregoing and other objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a perspective view of a portion of the frame of a steel structure constructed in accordance with my invention;

Figure 2 is a perspective view of a girder and its securing plate;

Figure 3 is a vertical sectional view approximately on line 3'-3' of Fig. 1;

Figure 4 is a perspective view of one of the locking-bands;

Figures 5 and 6 are views approximately on lines 5'-5' and 6'-6', respectively, of Fig. 1;

Figure 7 is a view in perspective of one of the binding sleeves adapted for holding registering ends of the supporting columns in relative fixed bearing relation;

Figure 8 is a perspective view of an intermediate portion of a column, to which is fixedly secured a supporting bracket, a securing band slidably encircling the column above the supporting bracket, and one end of a girder and its securing plate disposed above the securing band, preparatory to moving said end of the girder and securing band, relatively to the column and bracket, for interlocking and permanently securing said members together;

Figure 9 is a view in cross section of the girder and its securing plate;

Figure 10 is a perspective view of one of the supporting brackets;

Figure 11 is a vertical median sectional view through portions of a column, supporting bracket, securing band, girder and securing plate, fixedly secured together;

Figure 12 is a view approximately on line 12'-12' of Fig. 1; and

Figure 13 is a perspective view of one of the locking pins.

Referring to the drawings in detail, throughout which like reference characters designate like parts:

The numerals 1 and 2 designate the vertically extending columns and horizontally extending girders, respectively, of the present invention.

The columns, which are preferably formed of structural steel either of the usual I-beam or 2-piece channel-steel stock, have their lower ends disposed upon and secured, in any preferred manner, to a suitable foundation 3, formed preferably of concrete.

In the event that any of the columns 1 are found to be too short for the purpose intended, they may be extended to any suitable length by disposing two or more together end-to-end, in which position the two registering ends are maintained in fixed longitudinal alignment by means of a rectangular annular binding sleeve 4 fitted snugly around against the two abutting end portions of the columns,

extending about equidistant from the abutting end of each (see Figs. 1 and 3).

Intermediate the ends of the columns 1 are rigidly secured supporting brackets 5. These supporting brackets, which comprise, each, a vertical member 5^a, preferably riveted or welded to the sides of the columns 1, and a horizontally extending member 5^b projecting at right angles outwardly from the upper end of said vertical member. In the present illustrated form of the invention the supporting brackets 5 are secured by means of rivets 6, which pass through both the lower members 5^a of the brackets and the body portions of the columns 1.

Encircling the column 1 immediately above the bracket 5, and preferably seating on the latter, is a rectangular annular securing band 7, which is adapted to fit snugly, but normally operatively slidably, against the sides of the column, excepting, however, the side of the column against which is secured the supporting bracket 5. On this side it is spaced a suitable distance outwardly from the column to form a slot 7^a, the function of which will become apparent as the description proceeds.

Longitudinally across the length of the girders 2, are secured securing plates 8 by means of rivets 9. These securing plates are somewhat longer than the girders to which they are secured, to permit their ends being struck at right angles downwardly to form locking lips 10, which are spaced suitable distances outwardly from the squared ends of the girders, to form interlocking niches 10^a between the ends of the girders and said locking lips.

The ends of the girders 2 are disposed on their respective brackets, previously attached to the columns, and are permanently secured to said columns by slipping the locking lips 10 down into their respective slots 7^a as far as they can go, and disposing the adjacent sides of the securing bands 7 in the niches 10^a (see Fig. 11).

The dimensions of the interassociating parts of the locking lips 10, securing bands 7, relative to the slots 7^a and niches 10^a, should be such that when these parts are disposed in their proper positions for permanently binding the girders to the columns, the girders will bear firmly on their respective supporting brackets 5, and there will be substantially no longitudinal movement of the girders relative to the columns.

The securing plates 8 are preferably secured to the girders 2, and the supporting brackets 5 to the columns 1, at the shops or mills where the steel is prepared and before the same is delivered to the premises where the frame is to be erected.

Where two or more girders are disposed in the same horizontal plane and have ends attached to the same column but on different

sides thereof, obviously, there must be secured a supporting bracket 5 for each girder, and the securing band 7 will have to be made large enough relative to the transverse dimensions of the column to allow sufficient room between the latter and said band to permit the entrance therebetween of the locking lips 10 of each girder (see Figs. 5, 6 and 12). In the event of two or more girders being secured to the same column, as above stated, it will be found that this will result in rectangular vertical extending openings 11 being formed at the inner corners of the supporting bands at the intersections of the adjacent edges of the locking lips of each pair of girders disposed at relative right angles. These openings are preferably filled by driving closely fitted locking pins 12 thereinto (see Fig. 12).

The columns 1 may comprise a single length of steel, or, if preferred, as would likely be the case in the erection of tall structures, two or more columns may be butted together end-to-end, and held in longitudinal alignment by encircling the connected end portions of each pair of abutting columns with an annular rectangular sleeve 4. If said pairs of abutting columns are of unequal transverse dimensions, as would be the case if a smaller column was set on top of a larger one, the sleeve 4 should be made with unequal interior dimensions corresponding with the different dimensions of the columns, so as to fit snugly against the sides of each.

Having described my invention, what I claim and desire to secure by Letters Patent, is:

1. In a frame construction of the character described, the combination with a column having a supporting bracket secured thereto and projecting laterally outward therefrom, of a girder having one end supported upon said bracket, a band encircling said column, and a lip carried by said girder and disposed between the outer face of the column and the inner face of the band.

2. In a frame construction of the character described, the combination with a vertically extending column having a supporting bracket secured to and extending laterally outward beyond one side thereof, of a girder having an end portion bearing on and supported by said bracket, a lip carried by said girder, a band slidably encircling said column and embracing said lip.

3. In a frame construction of the character described, the combination with a vertically extending column, of a locking band encircling said column, a horizontally extending girder, a locking lip at one end of said girder extending across the end thereof in spaced relation thereto and disposed between a portion of said band and said column, and means carried by the column for supporting the girder.

4. In a frame construction of the character set forth, the combination with a vertically extending column having a supporting bracket on one side, of a securing band encircling said column above said bracket, a horizontally extending girder having one end portion resting upon and supported by said bracket, a securing plate fixedly secured to said girder and having a locking lip overhanging one end of said girder and in spaced relation thereto, said locking band having a portion disposed between said locking lip and girder whereby one end of said girder is held substantially in fixed relation to said column.
- 5 10 15 20 25 30 35
5. In a frame construction of the character set forth, a horizontally extending girder, and a securing plate extending longitudinally of said girder and fixedly secured to the upper side thereof, a free end portion of said plate extending downwardly across and in spaced relation to an end of the girder to form a locking lip adapted to interlock and cooperate with means carried by a column to secure the girder to the column.
6. In a frame construction of the character described, a column, a supporting bracket secured to said column, a girder resting at one end upon said bracket, a lip carried by said girder, and a band encircling the column and embracing said lip, all portions of said girder being disposed intermediate the ends of the column.

In testimony of the foregoing being my own, I have hereunto affixed my signature this 30th day of April, 1929.

JOHN GREEN.
